UNITED STATES PATENT OFFICE

2,309,145

TRUCK FOR EXPLOSIVES

Joseph E. Turnock, Riverton, N. J., and
James E. Kirk, Philadelphia, Pa.

Application November 7, 1941, Serial No. 418,132

2 Claims. (Cl. 280—50)

(Granted under the act of March 3, 1883, as
amended April 30, 1928; 370 O. G. 757)

The invention described herein may be manufactured and used by or for the Government for governmental purposes, without the payment to for handling explosive materials.

This invention pertains to a portable device for handling explosive materials.

It is an object of the invention to provide a hand truck for safely transporting explosive materials from one location to another.

The specific nature of the invention as well as other objects and advantages thereof will clearly appear from a preferred embodiment as disclosed in the accompanying drawings in which:

Fig. 1 is a view in side elevation of a practical embodiment of the invention.

Figs. 2 and 3 are respectively plan and end views thereof.

Fig. 4 is a plan view of the frame of the truck, and

Fig. 5 is a perspective view of one of the frame members.

The truck comprises a rectangular base 10 supported by a pair of axles 11 which are journaled in the hubs of four wheels 12. The base 10 cradles a box-like receptacle 13 which is arranged to carry the explosives. A U-shaped handle 14 is secured near one end of the frame to facilitate movement of the truck by an operator.

Referring to Figs. 4 and 5, the base 10 is preferably constructed of metallic angle members 15 which are arranged with their ends in abutting relationship and brazed at the lines of intersection 16. It has also been contemplated that a unitary cast base be employed in which instance brazing is unnecessary. The angle members 15 are provided with vertical flanges 17 and inwardly directed horizontal flanges 18. A pair of spaced metallic axles 11 are brazed to the under side of the base. The handle 14 is secured to one end of the base by suitable means such as brazing.

The above mentioned components are preferably made of metal for durability. Non-sparkable materials such as brass are employed so as to avoid the possibility of igniting explosive mixtures.

Wheels 12 equipped with resilient or pneumatic tires 19 are mounted on the axles. Brass hub caps 20 are secured to the wheels particularly when steel axles are employed.

Receptacle 13 is arranged to rest within the cradle formed by the vertical flanges 17 and the horizontal flanges 18 of the angle members 15 which comprise the base. The receptacle is preferably a wooden container provided with a hinged

top 21. Brass hinges 22 and a brass hasp 23 with a swivel stop 24 are secured to the lid and box by brass screws. The receptacle 13 is attached to the base 10 by similar screws 25. A pair of slotted brass lid supports 26 are pivoted to opposite sides of the lid and slidably engage a stud 27 secured to the receptacle. A pair of brass supports 28 are attached to the box and brazed to the handle 14 to impart rigidity to the latter. Wooden spacers 29 are removably fitted in grooves 30 in the interior of the container so as to divide it into a plurality of compartments.

The truck is slung low to the ground to give stability thereby reducing to a minimum the possibility of tilting or upsets. Resilient tires diminish the amount of vibration transferred to the contents of the truck during transportation. The employment of an integral metallic frame structure imparts strength and rigidity to the vehicle. By using brass or similar non-sparkable materials in the frame and other accessories, the danger of fortuitous explosions from sparking is negated. A wooden box structure reduces the cost of the hand truck and permits an easy replacement which may become necessary either because of ordinary wear or accident to the body.

We claim:

1. A hand truck for transporting explosives comprising, a base of non-sparkable metal having horizontal inwardly directed flange portions and vertical upwardly directed flange portions, a receptacle of non-sparkable material confined within said flange portions, a hinged top on said receptacle, spacers within said receptacle, a pair of axles secured to said base, a plurality of wheels mounted on said axles, non-sparkable hub caps on said wheels, and a handle of non-sparkable metal secured to said base and said receptacle.
2. A hand truck for transporting explosives comprising, a base of non-sparkable metal having horizontal inwardly directed flange portions and vertical upwardly directed flange portions, a receptacle of non-sparkable material confined within said flange portions, a hinged top on said receptacle, a lid support secured to said top and said receptacle, spacers within said receptacle, a pair of axles secured to said base, a plurality of wheels mounted on said axles, non-sparkable hub caps on said wheels, resilient treads on said wheels, and a handle of non-sparkable metal secured to said base and said receptacle.

CERTIFICATE OF CORRECTION.

Patent No. 2,309,145.

January 26, 1943.

JOSEPH E. TURNOCK, ET AL.

It is hereby certified that error appears in the printed specification of the above numbered patent requiring correction as follows: Page 1, first column, line 4, strike out the words "for handling explosive materials" and insert instead --us of any royalty thereon--; and that the said Letters Patent should be read with this correction therein that the same may conform to the record of the case in the Patent Office.

Signed and sealed this 9th day of March, A. D. 1943.

(Seal)

Henry Van Arsdale,
Acting Commissioner of Patents.
